TREATMENT OF DISTILLATE PETROLEUM FRACTION

Dennis George Adlington and Kenneth Tupman, Sunbury-on-Thames, England, assignors to The British Petroleum Company Limited, London, England, a British joint-stock corporation

No Drawing. Filed Oct. 14, 1960, Ser. No. 62,521
Claims priority, application Great Britain Oct. 20, 1959
14 Claims. (Cl. 208—264)

This invention relates to the treatment of distillate petroleum fractions boiling above 150° C. and particularly to the treatment of distillates boiling between 150 and 450° C., such as 150—250° C., 250—350° C. and 350—450° C. distillates, and the principal object of the invention is to provide a process by means of which the cloud point, pour point or freezing point of such fractions may be substantially lowered.

According to the process of the present invention, the distillate is contacted in the presence of hydrogen with a catalyst containing a group VIA metal on a refractory oxide support at a temperature of at least 750° F. but below the temperature at which substantial cracking occurs, a pressure which is greater than the equilibrium pressure and a space velocity of the liquid feedstock not exceeding 3.0 v./v./hr., the temperature and space velocity being correlated so that the cloud point, pour point or freezing point of the stabilized distillate is at least 10° F. lower than the cloud point, pour point or freezing point of the feedstock.

For the purposes of the present specification, substantial cracking is understood to occur when more than 20% wt. of the feedstock is converted to material boiling below 150° C. Preferably not more than 15% wt. of the feedstock is converted to material boiling below 150° C. The temperature employed is preferably above 800° F. and will not usually exceed 900° F. and in general the lower the temperature, the lower the space velocity.

The pressure employed will normally be between 100 and 1500 p.s.i.g. and the hydrogen to hydrocarbon mole ratio will normally be from 5 to 1 to 20 to 1.

The process of the present invention will normally lower all the three points specified, viz. cloud point, pour point and freezing point. The point to be taken as the criterion in any given operation will depend on the boiling range of the material being treated and the use to which it is to be put. In general the freezing point is only of significance with the lighter distillates.

By operation at a pressure which is greater than the equilibrium pressure there will be an overall consumption of hydrogen. The equilibrium pressure for any given temperature and space velocity is the pressure at which hydrogen consumption and hydrogen production are in balance and may be determined by commencing operation at a relatively low pressure and recycling all the hydrogen produced without any addition of extraneous hydrogen. As the hydrogen produced is recycled the pressure gradually rises until it reaches equilibrium.

The advantages of operating with an overall consumption of hydrogen are principally increased catalyst life, and the minimising or avoidance of a reduction of the diesel index.

Hydrogen may be added on a once-through basis, or it may be recycled.

2

The distillate fraction used as feedstock may have a low initial sulfur content, for example 0.1% wt. sulfur or less. Such low sulfur feedstocks may be straight-run materials or the products of previous refining treatments, for example, products of a hydrocatalytic desulfurization process. With feedstocks containing higher amounts of sulfur, the process according to the invention may result in a considerable reduction in the sulfur content. In the case of feedstocks having a low initial sulfur content, the process may be accompanied by an increase in specific gravity.

Some lower boiling material will be produced by, for example dehydrogenation, desulfurization and/or a small amount of cracking, and this is separated from the product, preferably by fractionation, to stabilize it and give a material of the required boiling range and flash point. A convenient cut point is in the region of 130—170° C.

The catalyst contains a group VIA metal preferably in the form of an oxide or sulfur on a refractory oxide support. The catalyst may also contain a group VIII metal, preferably in the form of an oxide or sulfur, in addition to the group VIA metal. The presence of a group VIII metal is particularly desirable if it is desired to desulfurize as well as to reduce the pour point. The preferred group VIA metal is molybdenum and the preferred group VIII metal is an iron group metal particularly cobalt. The group VIA metal may be present in from 5 to 30% wt. (expressed as oxide), by weight of total catalyst, and the group VIII metal from 0.1 to 5% wt. (expressed as oxide), by weight of total catalyst. A particularly preferred catalyst contains the oxides of cobalt and molybdenum (as such, or in combined form or both).

The refractory oxide support is preferably acidic and may be one or more of the refractory oxides of elements from group II, III or IV. Silica may be excepted from the suitable group IV refractory oxides. It may also contain from 0.1 to 6% wt., by weight of total catalyst, of a halogen, particularly fluorine or chlorine, or 1 to 25% wt. by weight of total catalyst, of phosphorus. Examples of suitable supports are alumina, with or without the stated quantity of halogen or phosphorus, titania-alumina, zirconia-alumina and beryllia-alumina.

The catalyst may be employed as a fixed bed, a moving bed, or in the fluidized state.

The degree of reduction in pour point is a function of the catalyst activity and in the case of a fixed bed process, in which the catalyst is not continuously regenerated, the greatest reduction in pour point is obtained during the early stages of a processing period. In such circumstances, the operating temperature may be gradually increased to compensate for loss of activity. Alternatively, continuous catalyst regeneration may be employed, using either a moving or fluidized catalyst bed process.

If desired, a part only of a particular distillate may be treated by the process according to the invention and the resulting product blended with the untreated portion of the distillate to give a final product of reduced pour point.

The invention will now be described with reference to the following examples:

EXAMPLE 1

A straight run gas oil having a boiling range of 249—349° C. ASTM was processed over a catalyst consisting

of 2.7% wt. cobalt oxide (CoO) and 15.5% wt. molybdenum oxide (MoO₃) on alumina and promoted with 3.34% wt. fluorine, in the presence of recycled hydrogen. The process conditions employed and the results obtained are set out in Table 1 below:

Table 1

Operating Conditions:					
Temperature, °F	680	825	900		
Space velocity, v/v/hr	1.0	1.0	8.0	10	
Pressure, p.s.i.g	220	1,000	750		
Recycle rate, s.c.f./b	500	6,000	1,000		
	Feed				
Specific Gravity, 60° F./60° F.	0.841	0.833	0.841	0.828	15
Sulfur content, percent wt	1.2	0.06	0.01	0.05	
Pour Point, °F	+15	+15	-15	+15	
Flash Point, °F	>235	>150	>150	>150	

This table shows that reduction of pour point is not obtained under all catalytic hydrogenation conditions which give rise to extensive desulfurization, but that it is necessary to employ simultaneously a low space velocity and a high reactor temperature.

EXAMPLE 2

A vacuum gas oil having a boiling range of 327° C. to 400° C. ASTM was processed over a catalyst consisting of 2.4% wt. cobalt oxide (CoO) and 14.2% wt. molybdenum oxide (MoO₃) on alumina, in the presence of recycled hydrogen. The process conditions employed and the results obtained are set out in Table 2 below:

Table 2

Operating Conditions:	Feed	Hours on Stream				
		10	25	50	100	175
Temperature, °F	900	900	900	900	900	40
Pressure, p.s.i.g	615	610	610	610	605

Pour Point, °F	60	20	40	40	45	
Flash Point, °F	150	150	150	150	150	

A vacuum gas oil having a boiling range of 327° C. to 400° C. ASTM was processed over a catalyst consisting of 3.2% wt. cobalt oxide (CoO) and 15.0% wt. molybdenum oxide (MoO₃) on alumina and promoted with 3.1% wt. fluorine, in the presence of recycled hydrogen. The process conditions employed and the results obtained are set out in Table 3 below:

Table 3

Feed	Hours on Stream				
	10	50	100	150	175
Operating Conditions:					
Temperature, °F	810	810	810	830	840
Pressure, p.s.i.g	1,000	1,000	1,000	1,000	1,000
Space Velocity, v/vhr.	1.0	1.0	1.0	1.0	1.0
Recycle Gas Rate, s.c.f./b	9700	9750	9625	9980	9915
Hydrogen Consumption, s.c.f./b					
Yields:	419	440	380	330	286
Gas, percent wt	3.9	3.7	3.8	5.3	5.8
Gasoline, percent wt	8.3	5.0	3.5	5.0	5.1
Gas Oil (Stabilized), percent wt					
Stabilized Gas Oil Inspection Data:	87.8	91.3	92.7	89.7	89.1
Specific Gravity, 60° F./60° F.	0.8915	0.8545	0.8555	0.8575	0.8555
Total sulfur, percent wt	2.38	0.01	0.01	0.01	0.01
Pour Point, °F	60	30	40	45	40
Flash Point, °F	150	150	150	150	150

This example shows that results similar to those in Example 2 were obtained at lower temperatures by using a fluorine promoted catalyst. It also demonstrates that the decline in catalyst activity can be compensated by increasing the operating temperature.

EXAMPLE 4

A gas oil having a boiling range of 234° C. to 350° C. ASTM and containing 1.13% wt. of sulfur was processed over a catalyst consisting of 3.2% wt. cobalt oxide (CoO) and 15.0% wt. molybdenum oxide (MoO₃) on alumina and promoted with 3.1% wt. fluorine, in the presence of recycled hydrogen. The process conditions employed and the results obtained are set out in Table 4 below:

Table 4

Diesel Index	60	59	55	62	54	56
Cloud Point, °F	18	6	-2	-2	-8	2
Pour Point, °F	15	5	-5	-5	-15	-5

This example shows that a substantial reduction of pour point is obtained particularly during the early hours on stream.

EXAMPLE 5

A gas oil having a boiling range of 234° C. to 350° C. 75 ASTM and containing 1.13% wt. of sulfur was processed

over a catalyst consisting of 1.4% wt. cobalt oxide (CoO) and 8.6% wt. molybdenum oxide (MoO₃) on a base of 4% wt. titania and 96% wt. alumina in the presence of recycled hydrogen. The process conditions employed and the results obtained are set out in Table 5 below:

Table 5

We claim:

1. A process for the treatment of distillate petroleum fractions boiling within the range 150–450° C. to lower the pour point at least 10° F. without material reduction in the specific gravity and diesel index of said distillate fractions, comprising contacting the distillate fraction as feedstock in a treating zone and in the presence of hydrogen with a catalyst containing a group VIa metal on a silica-free, refractory oxide support, the hydrogen to hydrocarbon mole ratio being from 5 to 1 to 20 to 1; maintaining a selected temperature and a selected space velocity in said zone, said selected temperature in said zone being maintained above 800° F. but not higher than about 900° F. and being a temperature at which, at said selected space velocity, not more than 20% wt. of the feedstock is converted to material boiling below 150° C. and said selected space velocity being at least equal to the space velocity at which at said selected temperature

not more than 20% wt. of the feedstock is converted to material boiling below 150° C. but not exceeding 3.0 v./v./hr.; maintaining a selected pressure in said zone which is greater than the equilibrium pressure of the feedstock at said selected contacting temperature and said

- selected space velocity but not greater than about 1500 p.s.i. ga., said selected temperature and said selected space velocity being correlated to reduce the pour point of the feedstock such that the pour point of the material of the treated distillate fraction boiling above 150° C. is at least 10° F. lower than the pour point of the feedstock, and recovering the treated distillate fraction.
2. A process as claimed in claim 1, wherein the feedstock contains 0.1% wt. or less of sulfur.
3. A process as claimed in claim 1 wherein the catalyst contains from 5 to 30% wt. (expressed as oxide), by weight of total catalyst, of a group VIa metal on a silica-free refractory oxide support.
4. A process as claimed in claim 3 wherein the catalyst contains from 5 to 30% wt., by weight of total catalyst, of molybdenum oxide (expressed as MoO₃).
5. A process as claimed in claim 3 wherein the catalyst contains also from 0.1 to 5% wt. (expressed as oxide), by weight of total catalyst, of a group VIII metal.
6. A process as claimed in claim 5 wherein the group VIII metal is an iron group metal.
7. A process as claimed in claim 6 wherein the catalyst contains from 0.1 to 5% wt., by weight of total catalyst, of cobalt oxide (expressed as CoO).
8. A process as claimed in claim 3 wherein the refractory oxide support is selected from the class of supports consisting of the silica-free refractory oxides of elements from group II, III and IV.
9. A process as claimed in claim 8 wherein the support contains from 0.1 to 6% wt. by weight of total catalyst, of halogen.
10. A process as claimed in claim 8 wherein the support contains from 1 to 25% wt., by weight of total catalyst, of phosphorus.
11. A process as claimed in claim 8 wherein the support is alumina.
12. A process as claimed in claim 8 wherein the support is titania-alumina.
13. A process as claimed in claim 8 wherein the support is zirconia-alumina.
14. A process as claimed in claim 8 wherein the support is beryllia-alumina.
